SPRING STRUCTURE

John H. Burr and Donald J. Driscoll, New Richmond, Wis., assignors to Strand Ski Company, New Richmond, Wis., a corporation of Wisconsin

Application September 12, 1942, Serial No. 458,068

7 Claims. (Cl. 5—239)

This invention relates to spring structures which are suitable for use in beds, mattresses and furniture generally.

Our principal objects are to provide a novel spring assembly of this class adapted to be constructed from wood, as a saving in the use of war materials, and to simplify and reduce the cost of such structures while affording adequate strength and resiliency.

The invention will be best understood by reference to the accompanying drawings in which:

Figure 1 is a plan view showing a typical unit of our improved spring structure;

Fig. 2 is an end view of the same;

Fig. 3 is an end view showing one arrangement of a plurality of our spring units in a wide spring or mattress and with portions of the supporting frame members shown in section;

Fig. 4 is a plan view showing an alternate form of top structure for our improved spring, and

Fig. 5 is an end view of the form of the invention shown in Fig. 4.

Our improved spring comprises two series of resilient, inclined members indicated by the numerals 5 and 6 respectively. The members 5 are normally parallel to each other and a bar 7 connects their lower ends together. This bar is preferably mortised to receive the ends of the several members 5 and a series of pins or screws 8 and/or adhesive may be used to fasten the members to the bar. The members 6 are similarly connected at their lower ends to a bar 9 and extend obliquely upward between the members 5, crossing them in a vertical plane located approximately midway between the bars 7 and 9. Each member 5 is thus spaced between a pair of the members 6, except those at the ends of the unit. Extending along the center line of the unit in parallel relation to the bars 7 and 9 is a rigid bar 10 which is formed with mortises affording bearings to receive and fit the several members 5 and 6 so that the latter are connected together approximately midway between their upper and lower ends. The upper ends of the members 6 are connected by a bar 11 which is also formed with mortises to receive the ends of these members 6, the fastening comprising adhesive or other suitable means such as the screws 12.

A flexible top is supported on the upper and outer ends of the members 5 and 6. As illustrated in Figs. 1, 2 and 3 this top comprises a series of flexible wood strips 13 which are severally fastened at one end to the bar 11 and normally extend horizontally across the spring structure, each strip 13 being located directly

above one of the members 5. The strips 13 rest on the upper ends 14 of the members 5 and are slideable thereon to allow for free bending of the several members. To retain each of the strips 13 directly above its supporting member 5, a stud 15 is mounted on each strip 13 and projects down through an elongated slot 16 formed in the member 5. Extending across the otherwise free ends of the strips 13 and connected to each is a flexible member 17 which affords a soft upper edge on the spring unit. A stout cord is preferably used as the member 17. Substantially horizontal supports 18 may be provided for the bars 7 and 9 on a bed or box spring frame or on the couch, chair or other article of furniture to be provided with the spring structure.

For a spring of considerable horizontal extent, such as that for a double bed or in a large mattress, two or more of my spring units may be arranged as indicated in Fig. 3. These units may be supported on parallel members, such as the members 19 and 20. In this case the soft flexible tie members 17 will ordinarily be located along the center line of the spring.

Referring to the top structure shown in Figs. 4 and 5, we provide flexible wood strips 21 each of which extends obliquely from the upper end of one of the members 5 to the upper end of the adjacent member 6. Normally, these strips are disposed horizontally and in parallel relation to each other. For a wide spring or mattress two units each comprising a series of members 5 and 6 connected by bars 7, 9 and 10 are preferably arranged side by side on the bed frame or supporting members 22 and 23. Along the top center line of the double spring the strips 21 project from each side beyond the center plane so that these members of the several units are free to be compressed independently of each other but overlap laterally to afford a continuous support for a mattress or for upholstery along the junction of the two units. At their outer ends the strips 21 are each fitted with an eye 24 and the several eyes along each lateral margin of the spring are connected by a stout cord or rope 25 which permits flexing and transmits movement from one to another of these strips. These cords 25 are anchored at their ends on the end strips 21 of each unit.

A downwardly projecting stud 26 is rigidly mounted beneath each of the eyes 24 to engage the member 6 below in an elongated slot therein. Similar studs 27 project downward from the inner ends of the several members 21 to severally engage the members 5 in slots 28. The lower

ends of the studs 26 and 27 are preferably fitted with stop members comprising washers 29 to provide a connection between the several top strips 21 and their supporting members 5 and 6. It will be understood that the studs 26 and 27 working in the elongated slots permit the necessary relative movement for flexing of the several members 5, 6 and 21 as the top structure is depressed in use. The form of invention shown in Figs. 4 and 5 has the advantage over that shown in Figs. 1 to 3 inclusive in that in the former there are no rigid members directly connecting the top strips to each other either along the margins of the units or along the center plane where the units overlap.

We prefer to construct the members 5, 6, 13 and 21 from thin and relatively wide strips of certain of the harder species of wood having fairly straight grain and high moduli of elasticity. Probably the best species of wood for our purpose is hickory, but other softer woods have been found to be satisfactory for the purpose. Our improved spring assembly may be enclosed in upholstery and ordinarily at least the top surface is covered with a fabric and suitable padding or cushions. When a load is applied to the top members 13 or 21 either directly or through the overlying upholstery, these members are variously bent to conform to the load which is transmitted to the outer and upper ends of the members 5 and 6. As these thin members 5, 6, 13 and 21 have a high degree of elasticity, they produce the desired resilient effect.

It will be evident that any depression of the spring top causes deflection in two or more of the members 5 and 6 both above and below the bar 10. The tying and reinforcing action of the bar 10 causes the upper and lower portions of each of the members 5 and 6 to be bent in opposite directions so that each of these members, which is normally straight, when deflected, assumes a flat S shape and the load is distributed substantially uniformly throughout the length of each of a large number of members. Obviously, this minimizes the strain and degree of bending of the individual spring elements.

The top strips 13 and 21 and members 5 and 6 are preferably constructed from stock of like cross sectional dimensions. These members when made of wood ordinarily are from one-eighth to one-quarter inch thick and from one to three inches in width, depending on the load to be carried and degree of resiliency desired, as well as the length of the several members. As illustrated, the bars 1, 9, 10 and 11 are also constructed from wood. It is to be understood, however, that other materials may be used in the construction of these members and that other types of flexible tops may be substituted for the strips 13 and 21 without departing from the spirit of our invention as defined in the appended claims.

By locating the bar 10 along the center line where the strips of the respective series cross, we take full advantage of the resiliency of the entire upper half of each strip which may be depressed independently of the other strips where flexible edge members such as the member 17 or 25 are employed. An important feature of our invention, as applied to bed springs, resides in the disposition of the inclined strips and the normally horizontal strips crossways of the bed. This prevents the condition known as a sagging spring under the weight of the occupant and insures conformity of the spring to the various curves of the human body.

A bed spring should conform to the body of the occupant notwithstanding the fact that the greatest concentration of weight is beneath the hips of the occupant and less pressure is exerted, in varying degree, by the shoulders, head and feet of the occupant. It will be understood that the corresponding areas of our spring are adapted to be deflected independently of each other to compensate for this normal distribution of weight and thereby support the occupant in the most comfortable and healthful position.

Having described our invention, what we claim as new and desire to protect by Letters Patent is:

1. A spring assembly having in combination, a series of normally straight, parallel, resilient members extending obliquely upward from one side toward the other side of the structure, a second series of similar resilient members crossing the members of the first series and extending obliquely upward in the opposite direction, a rigid bar connecting the several resilient members of both series near the line where they cross each other and being formed with inclined bearing surfaces engaging and extending along the upper and lower surfaces of each resilient member and a flexible top supported on the upper ends of the several resilient members.

2. A spring assembly having in combination a series of resilient strips extending obliquely upward in one direction, a second series of resilient strips crossing the strips of the first series and extending obliquely upward in the opposite direction each of said strips extending from one longitudinal side to the opposite side of the assembly and a top structure comprising a series of normally horizontal, resilient strips supported on the upper end portions of the strips of the first and second series, each of the strips of the top structure being supported individually at one end on a single strip of the first series and at its other end on a single strip of the second series and means connecting said normally horizontal strips with the underlying oblique strips near each of said end portions and permitting limited sliding movement of the horizontal strips relative to the underlying strips.

3. A spring assembly having in combination a series of resilient strips extending obliquely upward in one direction, each from the bottom of the assembly at one side to the top of the assembly at the opposite side, a second series of resilient strips crossing the strips of the first series and extending obliquely upward in the opposite direction from the bottom to the top of the assembly, side bars respectively connecting the strips of each series together at their lower ends and extending longitudinally of the assembly, a central bar connecting the strips of both series together along the line where those of the respective series cross each other, and a top structure comprising a series of normally horizontal strips supported on the upper end portions of the strips of the first and second series, each of the strips of the top structure being supported at one end on a strip of the first series and at its other end on a strip of the second series and means connecting the end portions of the normally horizontal strips to the underlying end portions of their supporting strips respectively, said connecting means permitting limited sliding movement of the horizontal strips relative to the supporting strips respectively.

4. A bed spring assembly comprising a plurality of similar units each extending longitudinally of the bed and each comprising a series of resilient

strips extending obliquely upward crossways of the bed, a second series of resilient strips crossing the strips of the first series and extending obliquely upward in the opposite direction crossways of the bed, means supporting said strips of the several series in inclined positions and a top structure comprising a multiplicity of normally horizontal, flexible strips extending crossways of the bed in parallel, spaced relation to each other, each of said horizontal strips being supported at an end, individually on the upper end portion of a single underlying inclined strip and connecting means near each of said ends permitting limited sliding movement of the horizontal strip relative to the underlying inclined strip.

5. A bed spring assembly comprising a plurality of similar units each extending longitudinally of the bed and each comprising a series of resilient strips extending obliquely upward crossways of the bed, a second series of resilient strips crossing the strips of the first series and extending obliquely upward in the opposite direction crossways of the bed, means supporting the strips of the several series in inclined positions and a top structure comprising a multiplicity of normally horizontal, flexible strips extending crossways of the bed in parallel, spaced relation to each other, the horizontal strips of one of said units projecting laterally between the top strips of the other unit and being severally supported near their ends, each on a single underlying oblique strip and the adjacent end portions of the horizontal strips being movable in parallel vertical planes independently of each other.

6. A spring assembly having in combination a series of resilient strips extending obliquely upward in one direction, a second series of resilient strips crossing the strips of the first series and extending obliquely upward in the opposite di-

rection, the strips of one series crossing those of the other series approximately midway between the ends of the individual strips, means for supporting said strips in said inclined positions, a top structure comprising a series of normally horizontal, flexible strips each having a vertically movable end portion directly supported on an end portion of one of said oblique strips and a flexible cord connecting the several vertically movable end portions of the normally horizontal strips together along a lateral edge of the assembly.

7. A bed spring assembly comprising in combination, a series of resilient strips extending obliquely upward crossways of the bed, each strip being normally straight and extending from the bottom substantially to the top of the structure, a second series of similar resilient strips crossing the strips of the first series approximately midway between the top and bottom of the structure and extending obliquely upward in the opposite direction crossways of the bed, a rigid bar supporting said strips of the several series in inclined positions and extending directly above and below the line where the strips of the respective series cross and a top structure comprising a multiplicity of normally horizontal, flexible strips extending crossways of the bed in parallel, spaced relation to each other, each of said horizontal strips being supported near an end individually on the upper end portion of a single underlying inclined strip and means connecting an end portion of each of said normally horizontal strips to the underlying inclined strip, said connecting means permitting limited sliding movement of the horizontal strip relative to the underlying inclined strip.
